INSULATOR ASSEMBLY

Edson S. Schmid, East Williston, N. Y.

Application December 9, 1947, Serial No. 790,617

2 Claims. (Cl. 191—32)

1

This invention relates to supports for third or current-carrying rails of electric railways and more particularly to the construction of the dielectric insulating element thereof with its associated elements that are in contact therewith.

The currently common arrangement is to have a solid one-piece porcelain insulator provide support for the third rail in an elevated position from railroad cross-ties, but during the war it became all but impossible to obtain such insulators. They are rather heavy, weighing as much as 16 pounds and they are fired in a kiln to obtain the glazed porcelain effect heretofore considered essential for not only dielectric properties, but in order to assure that such insulators meet the usual and generally imposed tests for compression, puncture, fracture absorbence, accumulation of grease, dirt or brine, and of course electrical resistance.

So an object of this invention is to devise an insulator that is as good, if not better than, present-day insulators that can be made in quantities quickly of materials and with facilities now amply available. Another object is to devise such an insulator that does not have to be fired in a kiln or indeed does not need to be glazed. Another object is to devise such an insulator that has significantly less weight than present-day insulators. A further object is to devise such an insulator of separable parts as a hollow column or base piece and unglazed non-ceramic cap pieces that can be used upon the column piece, either singly or in superposed or multi-deck arrangements. Other objects include the construction and arrangement involved in (1) associating the hollow column with base of the bracket that supports the wooden guard that is positioned above the third rail, (2) in associating with the cap piece of the insulator with the stirrup or chair on which the third rail rests, and (3) in details of construction that contribute to such associations.

The base of the usual insulator does not have to meet the same strict requirements as does the cap piece, so I propose to make the base of my insulator in hollow cylindrical or tubular form and of a self-hardening, tough, dense, hard dielectric nonmetallic mixed material that is either castable or extrudable. However, a better and more expensive material must be used for the cap piece for it must meet all of the requirements for third-rail insulators. To that end, I propose to employ a composite material whose constituents can be admixed and then pressure-molded into the desired contoured shape where-

2

after it needs to be subjected only to drying and never to glazing or firing or other temperatures requiring a kiln.

My improved insulator has many advantages. 5 among them are the facts that my insulator weighs only one-third as much as present-day insulators; that my composite insulator can be made under present-day conditions promptly and in the large quantity currently needed by electric 10 railroads (which today face a three-year delay in delivery of critically needed insulators); that my insulator assembly can be made much cheaper than present-day assemblies; and that my insulator has a resistance to "flash over" that 15 is about four times greater than enough; and that the independent column or tubular base of my insulator can be made in various heights to accommodate various weights (and heights) of running rails, whereas my cap piece is a universal 20 element that can be used with any height column so that a railroad can get the benefit of a much lesser inventory of different height complete insulators which is a present-day problem and so is the distribution of such different 25 height insulators for the right height insulator rarely seems to be on hand at the right place at the right moment. Another advantage along this latter line is that the cap pieces are usable in multiple tiers on a single column, when required so it is not necessary to send back to the 30 warehouse for special insulators for such emplacements.

Other advantages of my improved insulator arise from the fact that since the insulator cap 35 piece is pressure-molded and not fired or burned in a kiln, its dimensions can be controlled more accurately so that its top can be made quite flat and a slot can be made therein of such dimensions that the chair or stirrup that holds the 40 third rail in place can be completely countersunk therein with the result that the rail receives support from a full diameter of the flat top of the cap piece.

The best embodiment of the invention now 45 known to me has been chosen for illustration in the accompanying drawings, although it is to be understood that it has been chosen for illustrative and not limiting purposes because obviously there can be changes in detail so long as they 50 fall within the ambit of the appended claims—bearing in mind however the principle of patent law relating to reversal of parts.

In the accompanying drawings, Figure 1 is a 55 vertical sectional view taken along a railroad tie showing one rail and its associated third or

power rail supported, in accordance with this invention, on a special type of dual-part insulator while centered on a stirrup or saddle piece. The wooden strip protecting the third rail is shown supported by the usual bracket. Fig. 2 is an isometric view of the third rail with the usual bracket-supported guard strip therefor, and a sectional view of those parts including the insulator of this invention. Fig. 3 is an isometric view of the stirrup or saddle-piece of this invention. Fig. 4 is an isometric view, with parts broken away of the cap piece of the insulators of this invention. Fig. 5 is an isometric view of the column piece of the insulator of this invention. Fig. 6 is an isometric view of the lower section or portion of the bracket. Fig. 7 is a vertical sectional view with parts not in section, of the modified insulator of this invention.

In the drawings and especially in Figure 1, there is a railroad rail secured in place on a railroad tie 12 by means of spikes 13 and a fishplate 14. Adjacent the rail 11 and on the tie 12 is a bracket 15 that supports the insulator assembly 16 of this invention, which is made up of a separable hollow column or base piece 17 and cap piece 18. Resting in the cap piece 18 is a stirrup or saddle piece 19 in which nests the third or power-conducting rail 20. The column section 17 of the insulator assembly 16 is supported from the base section 21 of the bracket 15, which base section is provided with upstanding curved flanges 22 and 23 in which the column piece 17 tends to center itself.

The bracket 15 has at its upper section a laterally-extending arm 25 that supports the usual wooden guard or shield piece that protects objects from falling onto the third rail 20.

My dual insulator is made up of the hollow preferably cylindrical column piece 17 such as is shown in Figure 5. This column piece is cast or extruded of a hardened and compressed mixture of asbestos and cement, an example of which is currently marketed by Johns-Manville Corporation under the name of "Transite." The cap piece of the insulator of this invention is preferably a pressure-molded mixture of a phenolic binder with asbestos filler pressed with about 250 tons pressure and thereafter dried to a temperature between 240° F. and 300° F., but not fired. An example of such a material is currently marketed by the Garfield Manufacturing Company of Garfield, New Jersey.

The column piece of the insulator can be a section of what is now currently sold as a conduit for cables cut into lengths about 5½ inches long with a thickness of approximately 5/8 of an inch thick. The cap piece is approximately 1½ inches thick with an overall diameter at its greatest dimension of 8 inches and with a diameter with its top face of approximately 6 inches. The column weighs about 2½ lbs. while the cap weighs about 3 lbs.

The cap piece 18 of the insulator is provided with a flat top face 28 and a tapered skirt side portion 29 sometimes called a petticoat. This terminates in a flanged edge 30 for causing any liquids received by the insulator cap to drip therefrom at some distance from the column portion of the insulator. The underneath face 31 of the insulator cap is provided with a flat face 31 that terminates in an annular recess into which fits the upper end of the column section of the insulator as shown particularly in Figure 2. The cap piece 18 of the insulator is provided with a central bore or aperture 33 and also with a dia-

5 metrically extending depressed slot or groove 34 in the upper face 28 of the cap 18.

10 Into the latter slot 34 there is fitted the stirrup or saddle member 19, preferably formed as shown in Fig. 3 with a main body portion having upturned ears or lugs 35 and 36 at each end thereof and a depending U-shaped appendage or boss 37 welded in place. The boss 37 is adapted to fit into the bore 33 of the cap piece 18 and to be self-centering therein as shown in Fig. 2 and the stirrup or saddle 19 fits into the recess 34 so that the upper face or side of the stirrup 19 is flush with the upper face 28 of the insulator cap 18.

15 In the multi-deck or multi-tier modification shown in Fig. 7, the separable insulator assembly of this invention lends itself to the use of multiple insulator caps as shown in that figure wherein between the normal insulator cap 18 and the column piece 17 there can be interposed a second and preferably larger cap piece 38 whose lower face is constructed in principle like the lower face of the cap piece 18 so that the cap piece 38 will fit onto the upper edge of the column piece 17. The secondary cap piece 38 is provided with 20 an upstanding annular flange on its upper face adapted to fit into the annular recess 32 of the cap piece 18.

25 In operation, the column piece 17 is centered in the flanges 22 and 23 of the base plate 21 of the bracket 15. The cap piece 18 is then centered in supported position on the column 17 with the annular recess 32 of the cap piece 18 fitting over the upper end of the column piece 17 as shown in Fig. 2. The stirrup 19 is then fitted into the recess 34 in the top or upper face 28 of the cap piece 18 and centered in position by means of its depending U-shaped appendage 37 fitted into the bore 33 of the cap piece 18. The wings or lugs 35 and 36 of the stirrup 19 center the third rail 20 in anchored position on the insulator so that it will not slide therefrom. At the same time, the fact that the upper face of the stirrup 19 is flush with the upper face 28 of the cap piece 18 provides extended frictional contact between the base of the third rail and the top face of the cap which further tends to hold the third rail in place on the cap.

30 The advantages of this arrangement have been stated in the forepart of this specification.

I claim:

35 1. An insulator which comprises a separate unfired insulating cap element having a flat rail-supporting top with a depressed recess diametrically across the top and a bottom circularly grooved on its underside, a base section having curved flanges, and a non-ceramic columnar hollow cylindrical section engaging the circular groove in the top and the base section being held in place solely by weight of the rail supported by the insulator and composed of a molded material that is insulating while yet cuttable to length on the job whereby all parts are standard except the cylindrical section and that is readily cut to length to suit variable length installations thereof.

40 2. An insulator according to claim 1, with the addition of a third rail holding stirrup located in the diametrical recess and having an appendage centered in the bore of the cap element, the upper face of the stirrup being flush with the top of the cap element.
